INVENTOR
Joseph Codman

BY
Johnnetta Deamer
ATTORNEY

UNITED STATES PATENT OFFICE.

JOSEPH CODMAN, OF NEW YORK, N. Y.

COMBINATION JEWELRY.

Application filed July 17, 1922. Serial No. 575,495.

To all whom it may concern:

Be it known that I, JOSEPH CODMAN, a citizen of the United States, and resident of city, county, and State of New York, have invented certain new and useful Improvements in Combination Jewelry, of which the following is a specification.

This invention relates to jewelry, having reference particularly to variable or combination jewelry.

In the manufacture of jewelry, expensive jewels and other ornamental settings have generally been permanently fixed and mounted on a base, such as a finger ring, bracelet, scarf pin, brooch, locket, etc., whereby the article of jewelry is confined to but one specific use.

My invention has for its object the provision of a combination device of this character which may be converted into several different forms and employed for a variety of uses, whereby one expensive or ornamental element may be used in connection with several relatively inexpensive base, or supporting elements, thus providing a variety of different articles of jewelry at a relatively small initial cost of production.

In carrying out my invention, I provide one jewel-set or otherwise expensively or arbitrarily ornamented element, and a plurality of relatively inexpensive base-elements adapted for interchangeable connection with the ornamental element, and means for detachably connecting said elements, as hereinafter fully described and specifically set forth in the appended claims.

In the accompanying drawings forming part of this specification, Figure 1 is a side view of a finger ring illustrating one embodiment of my improvement.

Fig. 2 is an edge view showing the application of the invention for producing a gentleman's scarf pin;

Fig. 3 is a back view of the scarf pin drawn on an enlarged scale;

Fig. 4 is an enlarged fragmentary side view of the ring construction, shown in sectional elevation;

Fig. 5 is a sectional view taken on the line 5—5 of Fig. 4;

Fig. 6 is a face view illustrating the application of my invention as applied to a lady's brooch.

Fig. 7 is a part sectional view taken on the line 7—7 of Fig. 7;

Fig. 8 is a fragmentary sectional view illustrating a slight modification;

Fig. 9 is a side view illustrating a combined ring and watch;

Fig. 10 is a back view of the plate for containing ornamentation, and

Fig. 11 is a face view of a detached member employed as a fastening means when the device is used as a brooch.

In the drawings, 1 indicates the detachable element constituting a base for containing ornamentation, such as jewels 2 or any other suitable ornamentation, as insignia of a society such as Masonic emblems, college class emblems, etc.; or any suitable, either ornamental or useful device may be mounted on the plate 1, for instance, a watch 2^a, shown in Fig. 9 of the drawings.

The plate 1, is provided on its back with latch-members 3 having, respectively, a hole 3^a, a notch 4 for interlocking engagement with tongues 5 of recess 6 formed in the base member 7, which as shown in Figure 1, 4, 5, 8 and 9 constitute a finger ring.

As illustrated particularly in Figures 4 and 5 the finger ring 7 is laterally split, the adjacent split sections being spaced apart by means of a slide 8 which engages grooves 9 of the ring 7, one groove 9 being provided with an indentation 10 which engages the rounded end of a bolt 11 of the slide 8, said bolt being normally pressed outwardly by means of a contractile spring 12.

The ring 7 is sufficiently resilient to admit of moving the adjacent grooved parts towards and away from each other (when the slide is removed) sufficiently to insert the latches 3 and allow the tongues 5 to spring into the notches, whereupon the slide 8 may be replaced to maintain the elements in secure connection with each other, the spring-pressed bolt 11 automatically engaging the indentation 10 when the slide 8 is pushed into position, as shown in Figures 4 and 5 of the drawings. To remove the slide 8 it

is simply necessary to strike it a sharp blow on either end in order to disengage the bolt end from the indentation 10. This construction of finger ring may be adjusted to receive plates 1 of various lengths and slides 8 of various widths, thus providing means for accurately fitting the ring to fingers of various sizes.

When it is desired to convert the device from a finger ring into a scarf pin, as illus-

trated by Figs. 2 and 3 of the drawings, I substitute for the ring 7 a resilient base plate comprising a bow 13 and flat extensions 14 having, respectively, a recess 15 for engaging the notches 4 of the latch-members 3. As a further means for holding the element 1 to the base element I provide hingedly connected clamping members 16 attached to the member 1 which are held 10 over the extensions 14 by means of suitable springs 17. The bow 13 is further provided with a pin 18, adapted for insertion on a scarf in the customary and well known manner.

15 When it is desired to employ the element 1 in connection with a base element constituting a plate 19 of a brooch having the customary pin 19^a, said plate is provided with apertures 20 through which the latch-members 3 are extended, and a spring-bow 21 is provided for securing the elements together, said bow having oppositely located studs 22 which engage the hole 3^a of the latch-members 3, as shown in Fig. 7 of the 25 drawings.

In the modification illustrated by Fig. 8 of the drawings I have shown a finger ring, or base element comprising an endless ring 7^a having a shallow recess 6, a relatively 30 deep recess 6^a, and a resilient latch member 27 for engaging the tongue 5 of the recess 6^a, said latch member 27 automatically acting to fasten the plate 1 to the element 7^a. As a means for disengaging the latch member 35 27 from the tongue 5, I provide a normally outwardly extended bolt 23 having a stop 24 which bears against a helical spring 25 encased within a recess 26 of the element 7^a, whereby the element 1 can be detached 40 by forcing the bolt 23 inwardly until the latch member is released from engagement 45 with the tongue 5.

While I have illustrated and shown fair examples of the application of my invention, I do not desire to be understood as 45 confining myself to the specific details of the mechanical constructions shown, as under the spirit of my invention, I believe that I am entitled to the employment of 50 such variations of mere mechanical detail as may fall within the scope of the appended claims.

Having thus described my invention, what

I claim as new and desire to secure by Letters Patent, is:—

55 1. In a jewelry device, in combination, a split ring having a plurality of recesses therein, slideable means the movement of which will space the ends of the ring and maintain them in fixed position with respect to each other, a plate, a plurality of extensions carried by the plate and inserted within the ring recesses, and means engaging the extensions within the recesses.

60 2. In a jewelry device, in combination, a split ring, having a plurality of recesses therein, a plate, a plurality of extensions carried by the plate and inserted within the recesses and means expanding the ring causing an engagement of the extensions 70 within the recesses.

65 3. In a jewelry device, in combination, a split ring having a plurality of recesses therein, a plate, a plurality of extensions carried by the plate and inserted within the 75 recesses, and a slideable member the movement of which, between the ends of the ring, will expand the ring and cause an engagement of the extensions within the recesses.

70 4. In a jewelry device, in combination, a split ring having a plurality of recesses therein, a shoulder within each recess, a plate, a plurality of extensions carried by the plate and inserted within the recesses, 85 each extension having a recess corresponding to a shoulder and means expanding the ring causing each recess shoulder to engage an extension recess locking the plate to the ring.

80 5. In a jewelry device, in combination, a split ring having a plurality of recesses therein, a shoulder within each recess, a plate, a plurality of extensions carried by the plate and inserted within the recesses, 90 each extension having a recess corresponding to a shoulder and a slideable member, the movement of which between the ends of the ring, will expand the ring and cause each recess shoulder to engage an extension recess locking the plate to the ring.

95 Signed at New York city, in the county of New York and State of New York this 24th day of January A. D. 1922.

JOSEPH CODMAN.
